UNITED STATES PATENT OFFICE.

LOUIS A. PRESTEK, OF SEATTLE, WASHINGTON.

WRENCH.

Application filed January 17, 1923. Serial No. 613,198.

To all whom it may concern:

Be it known that I, LOUIS A. PRESTEK, a citizen of the United States, and a resident of Seattle, in the county of King and State 5 of Washington, have invented certain new and useful Improvements in Wrenches, of which the following is a specification.

This invention relates to an improvement in wrenches especially although not necessarily adapted for embodiment in wrenches of the socket type.

In certain types of wrenches, particularly in socket wrenches, it has been found a matter of extreme difficulty to so construct and 15 organize the head of the wrench or the part thereof which serves as or carries the work engaging means that this head will have the high degree of strength essential to enable it to carry out its intended purposes and at 20 the same time keep its size, form and weight within the limits essential to practical manipulation or working in the crowded spaces in which it is often necessary to use such wrenches.

25 One of the principal objects of the present invention is to provide a wrench of this character which is light in weight, compact, relatively small in size, well balanced and proportioned and at the same time possessed 30 of adequate strength to withstand the severe strains and stresses incident to its usage.

Other objects and advantages of the invention reside in certain novel features of the construction, combination and arrangement 35 of parts which will be hereinafter more fully described and particularly pointed out in the appended claims, reference being had to the accompanying drawings forming part of this specification, and in which:

40 Figure 1 is a perspective view, showing one embodiment of the invention;

Figure 2 is a view thereof in transverse vertical section;

45 Figure 3 is a bottom plan view, parts being broken away for the sake of illustration.

Referring to the drawings wherein for the sake of illustration the invention is shown embodied in a wrench of the socket type, the numeral 10 designates generally the head 50 of the wrench which is provided with an axial opening 11 of polygonal form adapted to coact with the operating means 12 shown diagrammatically in dotted lines in Figure 1. It is to be understood that this operating means may be of any known or desired 55 form and preferably it includes a shank or

stud adapted to be fitted in the bore or opening 11 and to be held therein by a set screw 13. The operating means for the wrench forms no part of the present invention and 60 may be of any type of construction.

The head 10 is preferably constructed of hardened steel and at the end thereof opposite the opening 11 it is provided with a socket 14 of hexagonal form. This socket 65 14 constitutes the work engaging means of the wrench. The periphery of the head around the socket 14 has formed therein an annular channel 15. This channel extends 70 entirely around the socket 14 and for practically the entire length thereof although terminating short of the lower end of the wrench in order to leave an annular flange 16 for a purpose which will hereinafter appear. A wrapping of steel wire, designated 75 17 at 16, is wound on the head 10 within the channel 15. This wrapping 17 is wound on the head under great tension and the turns of this wrapping are soldered or otherwise secured to each other and to the head 10 80 in order to hold or secure the wire on the head and in the channel 15. It is to be noted that the flange 16 serves to prevent downward displacement of this wrapping and this flange in conjunction with the 85 other wall of the channel and a thin steel bushing 18 serves to house and protect the wrapping. The bushing 18 is fitted on the head so as to enclose the wrapping of wire shown in the drawings and this bushing is 90 welded or otherwise suitably secured in position. Of course it is to be understood that the turns of the wire 17 may be welded or otherwise secured in position in lieu of being soldered as above indicated. By placing the wrapping 17 under great tension and securing the turns of this wrapping to 95 each other and to the head 10 in the channel 15 around the work engaging means of the wrench the wrench is greatly reinforced 100 and strengthened where strength and capacity to resist strain is most needed, and this is accomplished without increasing the weight of the wrench and without impairing its susceptibility of embodiment in a compact and balanced structure capable of use and convenient manipulation in crowded and difficult or inaccessible places.

I claim:

1. A socket wrench having a head of 110 hardened steel formed with a work engaging socket, said head being provided with

an annular channel in its periphery, a wrapping of steel wire wound under tension in the channel of the head, the turns of the wrapping being soldered to each other and 5 to the head, and a bushing fitted on the head and secured thereto and enclosing said wrapping of wire.

2. A socket wrench having a head formed with a socket and provided with a channel 10 in its periphery, a wrapping of wire wound under tension in the channel of said head and secured to said head, and a bushing enclosing said wrapping.

3. A socket wrench having a head formed 15 with a socket and provided with a chan-

nel in its periphery, said channel encircling the socket, and a reinforcing wrapping of wire wound under tension in the channel of said head and secured therein.

4. A wrench having a head provided with 20 work engaging means and formed with a channel surrounding said work engaging means, and a reinforcing wrapping of wire wound under tension in the channel of said head and secured therein.

5. A wrench having work engaging means, and a reinforcing wrapping of wire wound under tension, surrounding said work engaging means, and secured thereto.

LOUIS A. PRESTEK.
